Primary Examiner — Mark Goodwin(74) *Attorney, Agent, or Firm* — Young & Thompson**CLAIM**

The ornamental design for cover plate for electrical devices, as shown and described.

DESCRIPTION

FIG. 1 is a top, front, and side perspective view of a cover plate for electrical devices showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the left of FIG.

2; and,

FIG. 7 is a side elevational view thereof from the right of FIG. 2.

The portions of the design shown in broken lines show unclaimed subject matter.
